UNITED STATES PATENT OFFICE

CARL G. PREIS, OF LYNBROOK, NEW YORK

CONCRETE ANCHOR

Application filed March 28, 1928. Serial No. 265,300.

My invention relates in general to metal fastening devices for concrete work and has particular reference to a so-called concrete anchor or insert designed for securing to concrete floors, walls, ceilings or other cement structures, such articles as hangers, beams, shafting, machinery and the like.

The main object of my invention is the provision of a concrete anchor or insure which is of simple construction, inexpensive to make and which is of such configuration that it obtains a maximum amount of support from the surrounding concrete and is securely held therein against displacement and can withstand great strains.

Another object of the invention is the provision of a concrete anchor or insert having a bell-shaped or spherical upper chamber and an outwardly flaring lower chamber which co-operate with a removable rocker nut to form a ball and socket connection with large bearing surface, assuring even distribution of load with less danger of breaking of anchor housing, permitting maximum radial and axial adjustability of the supporting bolt and locating the point of greatest strain as far from the entrance part of the insert as possible, where the anchor housing because of its shape and the support it receives from the surrounding concrete is the strongest. Numerous other objects and advantages of the invention will be apparent as it is better understood from the following description, which, taken in connection with the accompanying drawings, discloses a preferred embodiment thereof.

Referring to the drawing:

Fig. 1 is a side elevation of my invention partly broken away to show the interior construction more clearly.

Fig. 2 is a partial view of the temporary fastening lugs.

Fig. 3 is a cross-sectional plan view taken along the line 3—3 of Fig. 1.

Referring now more in detail to the drawings, and especially to Fig. 1 thereof, the preferred embodiment of my invention comprises a concrete anchor housing of cast iron or other suitable metal having a top wall 11, which in the present instance is flat, terminat-

ing into an annular projecting flange 12, an annular side wall 13, which is rounded or spherical in part and extends downwardly and then inwardly to form an inward shoulder or constricted throat part 14, and then flares outwardly at 15 in a substantial straight line, terminating into a lateral annular flange 16. Said annular flange 16 has at two opposite points bifurcated projections which form notches 17 which are to receive a fastening screw or nail to temporarily fasten the anchor housing to a mold, frame or scaffolding until the concrete or cement material has been poured around the anchor housing and has set and dried. It will be noted that the inward shoulder or throat part 14 divides the anchor housing into two parts, namely, into an upper and inner bell-shaped or spherical chamber 18, and a lower and outer outwardly flaring part 19.

The holding or anchor nut 20 which may be inserted or removed after the anchor housing has been permanently embedded into the concrete, is elongated, with a straight top, straight sides and bottom, and curved or rocker-shaped ends 21 which engage and correspond with the curved or spherical inner surface of the wall part 13, so as to form with said wall part 13 and the constricted throat 14, a ball and socket or universal joint connection with a maximum amount of bearing surface. The nut 20 has a central threaded perforation 22 to receive the threaded end of the supporting bolt 23 whose opposite end terminates in a screw nut 24. As illustrated in dotted-line position, the supporting bolt 23 may be swung or tilted radially in any direction from the position of natural rest shown in full lines. This radial adjustability or change of position of the supporting bolt is made possible by the universal joint connection between the rocker nut 20 and the curved inner wall of the bell-shaped chamber, and the extent of adjustability is limited only by the angle of the outward flare of the wall of the lower chamber of the anchor housing.

The supporting bolt 23 is also adjustable longitudinally, that is to say, there is sufficient head room between the top of the holding nut 20 and the top wall 11 of the housing.

to permit the bolt to be screwed into the holding nut 20 so that the screw-threaded end of the bolt will project a more or less distance beyond the straight top of the holding nut 20. This will permit a tightening or loosening of the bolt to accommodate variations in the dimension of the article supported by the bolt 23. In order to stop the rocker nut 20 from turning when the bolt 23 is screwed home, integral lugs 25 are provided at opposed points of the inner wall of the bell-shaped chamber. It will be readily appreciated by those skilled in the art that it is the novel exterior and interior construction and configuration of the anchor housing and the novel construction and co-operating shape of the rocker nut 20 which make this concrete anchor or insert superior to any similar device of which I am now aware.

20 The point of greatest strain in my improved construction is located far from the opening into the housing at the constricted throat part 14, which forms an outer concavity which is filled out and greatly reinforced by the surrounding concrete. Another such concavity or hollow is formed between the projecting flange 12 and the depending wall part 13, and this hollow also is filled out with concrete which helps to support the upper part of the housing and greatly assists in securing the same against displacement. This borrowing of the strength of the concrete at the most strategical point is peculiar to my invention, and permits the use of much lighter castings with attendant economy than has heretofore been thought possible and the employment of even drawn sheet metal anchor housings.

What I claim as new and desire to secure by Letters Patent of the United States, is:

40 1. In a concrete anchor in combination, an anchor housing having a rounded upper chamber, a constricted throat a substantial distance from the housing entrance and a lower chamber with outwardly flaring wall, a rocker shaped anchor nut removably positioned in said rounded upper chamber and supported by said throat and forming with said chamber a ball and socket joint, and a supporting bolt threadedly engaged with said nut and radially tilttable in all directions.

45 2. In a concrete anchor, in combination, an anchor housing having a rounded upper chamber, a constricted throat part and a lower chamber with outwardly flaring wall, said anchor housing being also provided with a top flange and a bottom flange, said constricted throat part and said flanges forming with adjacent housing parts a corresponding number of concavities which, when embedded in a concrete structure, provide annular lines of reinforcement for said housing, and a supporting means removably secured in said upper chamber and radially tilttable in all directions.

3. In a concrete anchor, in combination, an anchor housing having a rounded upper chamber, a constricted throat a substantial distance from the housing entrance and a lower chamber with outwardly flaring wall, 70 a rocker shaped anchor nut removably positioned in said rounded upper chamber and supported by said throat, and forming with said chamber a ball and socket joint and a supporting part threadedly engaged with said nut and radially tilttable in all directions, said upper chamber having integral lugs to limit rotation of said anchor nut.

4. In a concrete anchor, in combination, an anchor housing having a rounded upper 80 chamber, a constricted throat part a substantial distance from the housing entrance and a lower chamber with outwardly flaring wall, a rocker shaped anchor nut removably positioned in said rounded upper chamber and supported by said throat and forming with said chamber a ball and socket joint and a supporting part threadedly engaged with said nut and radially tilttable in all directions, 85 said lower chamber having means for securing said anchor housing in proper position until it is fully set in the concrete.
